UNITED STATES PATENT OFFICE.

WILLIAM H. BROWN, OF MARGARETVILLE, NEW YORK.

ANTISKID DEVICE.

1,238,490.

Specification of Letters Patent. Patented Aug. 28, 1917.

Application filed January 23, 1917. Serial No. 143,867.

To all whom it may concern:

Be it known that I, WILLIAM H. BROWN, a citizen of the United States, residing at Margaretville, in the county of Delaware 5 and State of New York, have invented a new and useful Antiskid Device, of which the following is a specification.

The present invention appertains to anti-skid devices for use upon the pneumatic or other tires of automobiles and other vehicles, and it is the object of the invention to provide a novel and improved device of that character for facilitating traction and preventing skidding, the device being of special 10 construction in order to obtain a firm grip or hold on the ground, ice, snow, or the like, it being simple and inexpensive as well as efficacious.

With the foregoing and other objects in view, which will appear as the description proceeds, the invention resides in the combination and arrangement of parts and in the details of construction hereinafter described and claimed it being understood that changes 15 in the precise embodiment of the invention herein disclosed, can be made within the scope of what is claimed, without departing from the spirit of the invention.

The invention is illustrated in the accompanying drawing, wherein:—

Figure 1 is a fragmental plan view of the anti-skid device or chain, illustrating two of the shoes.

Fig. 2 is an end view of one of the shoes 35 illustrating the curvature thereof to conform to the transverse curvature of the tire.

Fig. 3 is a cross section taken on the line 3—3 of Fig. 1.

The present device embodies a series of 40 shoes 1 to surround the tire; and said shoes are of cruciform or X-shape. The shoes are drop forged from suitable metal and are relatively thin, to fit snugly against the tread of the tire. The tongue-shaped arms 2 of each 45 shoe are disposed in oblique or diagonal arrangement, two arms projecting along diverging lines toward one side and the other two arms projecting similarly toward the other side. Between the ends of said pairs 50 of arms, the shoe is curved on an arc, as seen in Fig. 2, to conform to the transverse curvature of the tire. The edges of the arms 2 are rounded off as seen in Fig. 3, to prevent the chafing of the tire, and the arms are 55 relatively broad or wide to have a broad

bearing against the tire. The ends of the arms 2 are rounded and said arms are provided adjacent to their ends with slots or apertures 3 for the engagement of four short chains or flexible elements 4 which diverge toward the opposite sides and which have their remote ends connected with longitudinal chains or flexible elements 5 which extend around the opposite sides of the tire T, whereby to hold the shoes in place. The 60 flexible elements 4 being disposed obliquely or diagonally will prevent the displacement of the shoes when the wheel rotates in either direction, the pull being properly transmitted from each shoe by the elements 4 to 70 the elements 5.

The shoe 1 is provided with an integral cruciform or X-shaped rib 6 extending from its outer face with arms 7 extending along the intermediate portions of the arms 2 of 75 the body of the shoe. The arms 7 terminate short of the slot or apertures 3, whereby the ends of the arms 7 which extend close to the apertures 3 will in engaging the underlying surface protect the connections between the elements 4 and shoe as much as possible. The arms 7 of the rib are V-shaped cross section, as seen more clearly in Fig. 3, and the arms 7 are relatively narrow, leaving relatively wide bearing surfaces of the 80 arms 2 extending completely around the arms 7 of the rib.

The present shoe has V-shaped portions projecting in opposite directions longitudinally of the tire, and in opposite directions 90 transversely of the tire, whereby to facilitate traction or to cause the wheel to obtain an effective grip on the ground or underlying surface when the wheel is rotated in either direction, and to prevent the lateral skidding of the tire. The body portion of the shoe provides a broad bearing surface to engage the road, the edges of the body also being engageable with the ground, ice, or the like, to prevent slipping, and the rib 100 6 being engageable into the ground, ice, or the like, said rib having a relatively sharp edge. The construction is such that the shoe will not become clogged with snow, ice or other foreign matter, and provides a practical and desirable means for accomplishing the desired end.

Having thus described the invention, what is claimed as new is:—

An anti-skid shoe of cruciform shape 110

having relatively broad arms diverging toward opposite sides, the shoe having a cruciform rib projecting therefrom with its arms extending between the edges of the aforementioned arms and terminating short of the ends thereof, the end portions of the first mentioned arms having apertures beyond the ends of the second mentioned arms for the attachment of retaining means, the second

mentioned arms being relatively narrow and V-shaped in the cross section.

In testimony that I claim the foregoing as my own, I have hereto affixed my signature in the presence of two witnesses.

WILLIAM H. BROWN.
